UNITED STATES PATENT OFFICE.

HARRY DIMOND, OF BROOKLINE, MASSACHUSETTS.

ROLLING DEVICE FOR COTTON SAMPLES.

Application filed June 30, 1924. Serial No. 723,227.

To all whom it may concern:

Be it known that I, HARRY DIMOND, a citizen of the United States, residing at Brookline, in the county of Suffolk, Commonwealth of Massachusetts, have invented certain new and useful Improvements in Rolling Devices for Cotton Samples, of which the following is a specification.

This invention relates to an improved rolling-device for use with cotton sample tables for rolling the cotton into paper-wrapped bundles.

The principal object of the improvement is to provide means for expeditiously and conveniently rolling the cotton samples into a bundle while wrapping a sheet of paper therearound and turning in flaps at the ends to hold the cotton in place.

Another object of the invention is to provide a device of the type specified which may be employed as an attachment for the usual sample display table or constructed as a permanent part of the table itself.

Another object of the invention is to provide a device of the type specified which is simple in construction and economical to manufacture.

Further objects of the improvement are set forth in the following specification which describes a preferred embodiment of the invention as illustrated in the accompanying drawings. In the drawings:

Fig. 1 is a perspective view of a cotton sample table showing my improved rolling-device as applied to use therewith;

Fig. 2 is an end elevation of the rolling-device;

Fig. 3 is a plan view of the same;

Fig. 4 is an end elevation illustrating a modified form of the device;

Fig. 5 is an enlarged end view of one of the side-boards for the table showing it folded flat thereon; and

Fig. 6 is a view illustrating the manner in which the side-boards are arranged to guide the flaps of the paper around the cotton.

Referring first to Fig. 1 of the drawings, I have herein illustrated a cotton sample table 2 of conventional type having a relatively low flat top 3 supported from legs 4. At one end of the table 2 is a holder for the roll 5 of wrapping paper comprising uprights 6 having bearings for the stick or rod 7 around which the paper is rolled.

At the opposite end of the table 2 is the bundle-rolling device indicated in general by the reference character 10. As herein illustrated the rolling-device is constructed separate from the table to be attached across the end thereof, but it is to be understood that it may be built into the table as a permanent part thereof. The rolling-device 10 consists essentially of a roller-box 11, preferably constructed of wood, with its sides 12 of a length to adapt it to extend across the full width of the table 2. When made separate from the table the roller-box 11 is supported from two opposite legs or standards 13 formed by the end boards 70 of the box. In this form the roller-box 11 is fastened to the table 2 by means of angle-iron brackets 14 indicated in Figs. 1 and 3, or any other suitable attaching clamps or braces may be employed.

Adjacent the ends of the box 11 are cross strips or braces 15, see Figs. 2 and 3, which provide bearing-supports for a pair of parallel rollers 16. The rollers 16 may have end-gudgeons 17 journaled in suitable holes 80 extending through the braces 15 to mount the rollers in close parallel relation with their peripheries projecting slightly above the top of the box as shown in Fig. 2.

Extending between the ends of the box 85 and the cross-braces 15 are a series of parallel rods 19 between which are mounted two opposite arms or slides 20 adapted to slide up and down while riding against the end boards or legs 13. The arms 20 are provided at the top with bearing holes 21 adapted to receive a horizontal cylindrical rod or roller 22 which serves as the spindle or mandrel around which the cotton and its wrapper is wound as indicated in Fig. 95

1. One end of the roller or mandrel 22 is made square and fastened to a crank-handle 23, by means of which it may be rotated to wind the cotton therearound in the manner as hereinafter more fully explained. As 100 shown in Figs. 1 and 2, suitable weights 24 are fastened to the arms 20 at their lower ends whereby to draw them down to hold the roller or mandrel 22 under tension with the package resting on the under rollers 16 105 in the box 11.

In some cases I have found it preferable to control the arms or slides 20 from a central weight 25 shown in Fig. 4 as suspended from cords 26. The cords 26 pass 110

over pulley sheaves 27 within the box 11 and thence lead through pulleys 28 at the bottom of the legs 13 with their ends attached to the bottom of the arms 20. It will be seen, therefore, that the weight 25 tends to draw the arms downward and as the arms are raised with the increase in size of the package or bundle being wound onto the mandrel 22 the cords will be taken up to raise the weight.

Extending longitudinally of the top of the table 2 are two opposite folding side-boards 30 disposed a slight distance in from the edges of the top 3. Referring to Figs. 5 and 6, a relatively narrow strip or rail 31 is screwed or otherwise fastened to the top 3 of the table at each side thereof with its outer edge beveled off at an angle of forty-five degrees. A wider board 32 having a correspondingly beveled edge is hinged to the strip 31 at 33 to adapt it to fold upwardly at right-angles to the top of the table; while another still wider board 34 has its side hinged at 35 to the top of the strip 32 with the meeting edges beveled. The hinges allow the boards to be laid flat along the outer sides of the table when not in use, as shown in Fig. 6, while their beveled edges adapt them to be folded upwardly and inwardly as illustrated in Fig. 1 and shown by the dotted lines in Fig. 6, thus making a substantially inverted L-shaped trough or guideway for directing the side flaps *p* of the strip of paper *P* across the edges of the layer of cotton spread across the paper.

Having now described the construction of my improved rolling-device in detail its method of operation will next be explained. The side-boards 30 are first folded flat against the top of the table, as illustrated in Fig. 6, and the sheet of paper *P* unrolled from the roll 5, shown in Fig. 1, and drawn forward toward the roller-box 10. The cotton is now spread across the sheet of paper *P* and the side-boards 30 folded upwardly and inwardly to turn the marginal flaps *p* of the paper over the edges of the layer of cotton. The leading end of the paper *P* is then fastened to the roller or mandrel 22 by doubling it therearound with its marginal flaps *p* folded inwardly, and usually the edge of the paper is moistened to make it adhere better to the roller, it being understood that the roller 22 is first inserted in place in its bearings 21 in the arms 20.

Now as the crank 23 is turned to rotate the roller 22 the latter will wind up the paper *P* and with it the cotton *C*, forming a substantially cylindrical roll or bundle with the marginal flaps of the paper strip guided by the side-boards 30 to turn or fold them into the ends of the package to

hold the cotton in place. As the bundle builds up around the rod or mandrel 22 with its under side resting upon and riding on the rollers 16 the mandrel 22 will be gradually raised with the arms 20 sliding upwardly through the box 10. The weights 24 on the arms 20 act to resist the upward movement of the mandrel 22 and thus exert a pressure to hold the bundle against the under rollers 16 so that the cotton is compressed to form a firm, compact bundle with the paper wrapped snugly around the layers in a spiral with its side flaps turned in at the ends to protect the cotton. It will be understood that the strip of paper *P* is severed from the roll in a length sufficient to enclose the layer of cotton with a margin to cover the end thereof. After the full length of the strip has been rolled up in the manner above explained the crank 23 is given a short reverse turn to loosen the mandrel 22 from the end of the paper so that it may be drawn out from the center of the bundle after the latter has been tied with a cord wrapped therearound.

It will be observed from the foregoing that my invention provides a particularly simple and practical device for rolling up bundles of cotton samples. Such samples are used very generally for transporting and displaying different grades of cotton and are handled in large numbers by cotton brokers in purchasing and selling the staple. It is usual to spread the samples on display tables to exhibit them to buyers and where it is required to transport the samples to other locations the general practice is to roll them up in a sheet of wrapping paper with flaps turned in at the ends to hold the cotton in place and with a cord or rope tied on the outside of the bundle. In accordance with the usual practice of rolling the bundles entirely by hand it requires three men to roll a single bundle, one to rotate the mandrel and two more at the sides of the table to fold in the flaps that hold the cotton in place.

With the present improved device one man can expeditiously and conveniently roll the bundle in much less time than three men by the usual slow hand process and the completed bundles are more compact and uniform in size, so that they can be handled and stored to greater advantage. The reduction in the size of the bundle for a given amount of cotton is quite important because it is usual to store a large number of the bundles or packages in offices and show-rooms where the space is valuable owing to high rents. My improved device may be constructed as a permanent part of the sample table or employed as an attachment thereto, and besides producing more uniform and compact bundles its use

results in a considerable saving of time for combination with a cotton sample table of rolling the bundles. Moreover, the device is simple in construction and economical to manufacture and practically indestructible in use.

While I have herein shown and described my invention in its preferred form, it is to be understood that various modifications may be made in the structure and arrangement of the device without departing from the spirit or scope of the invention.

Therefore, without limiting myself to the exact embodiment illustrated, I claim:

1. In a bundle-rolling device for cotton sample tables, the combination of a rotatable mandrel on which the bundle is rolled, rotatable rollers for supporting the bundle as it is rolled on the mandrel, means for mounting the mandrel to allow it to recede from the rollers as the bundle increases in size while resisting its movement to cause the rollers to compact the bundle around the mandrel, and means to guide the paper wrapped around the bundle to fold its marginal portions into the ends thereof.
2. In a device of the type specified, the combination of a pair of horizontal rollers, a mandrel rotatable above the rollers, manually operable means for rotating the mandrel, movable arms for supporting the mandrel to adapt it to recede from the rollers as the bundle increases in size, means acting on said arms to resist the receding movement of the mandrel whereby to cause the rollers to compress the bundle around the mandrel, and means for guiding the paper wrapped around the bundle to fold its marginal portions into the ends thereof.
3. In a device of the type specified, the combination with a cotton sample table, of a pair of horizontal rollers extending thereacross, a mandrel supported above the rollers, manually operable means for rotating the mandrel, slidable arms provided with bearings for the mandrel, means acting on said arms to resist their sliding movement to hold the bundle against the rollers to cause it to be compacted to a minimum size, and means for guiding the paper wrapped around the bundle to fold its marginal portions into the ends thereof.
4. In a device of the type specified, the

a roller-box attachable to the end of said table, a pair of horizontal rollers journaled in said box, a pair of arms vertically slidable at the ends of the box, a mandrel rotatably mounted on said arms, weights on said arms for resisting the upward movement of the mandrel, and a crank for turning the mandrel.

5. In a device of the type specified, the combination of a roller-box having cross-braces spaced inwardly from its ends, a pair of horizontal rollers journaled at their ends to said braces, arms slidable through the box between the cross-braces and the ends thereof and provided with bearings at their upper ends, a mandrel rotatable in the bearings on the arms, a crank for rotating the mandrel, and weights connected with the arms to resist the rising movement of the mandrel away from the rollers.

6. In a device of the type specified, the combination of a sample table, side-boards extending longitudinally of said table and adapted to be folded flat thereagainst or to be raised into position to overhang the table to form inverted L-shaped guides, a rotatable mandrel at the end of the table, manually operable means for rotating the mandrel to wind a bundle thereon, rollers for supporting the bundle as it is wound on the mandrel, and means to resist the movement of the mandrel away from the rollers as the bundle increases in size.

7. In a device of the type specified, the combination of a cotton sample table, two-part side-boards hinged to the top of the table to adapt them to fold flat thereagainst or to be raised into position with one board perpendicular to the table and the other at right-angles thereto, rollers at the end of the table for supporting the bundle, a rotatable mandrel arranged above the rollers to adapt the bundle to be rolled thereon, manually operable means for rotating the mandrel, and means to support the mandrel to allow it to recede from the rollers as the bundle increases in size while maintaining the latter pressed against the rollers.

In testimony whereof I affix my signature.

HARRY DIMOND.
